CLAIM

The ornamental design for a garden marker stake, as shown and described.

DESCRIPTION

FIG. 1 is a side elevational view of a garden marker stake showing my new design, with a sign shown in broken lines in two alternate positions for illustrative purposes only;

FIG. 2 is an end elevational view thereof, taken along the line 2—2 of FIG. 1;

FIG. 3 is an opposite end elevational view thereof, taken along the line 3—3 of FIG. 1;

FIG. 4 is a top plan view thereof, taken along the line 4—4 of FIG. 1; and

FIG. 5 is a bottom plan view thereof.

FIG.1

FIG.2

FIG.3
